UNITED STATES PATENT OFFICE.

ANTONIO GOVERNATE, OF BROOKLYN, NEW YORK.

DESIGN FOR A PANEL FOR BEDSTEAD ENDS.

Application filed April 17, 1925. Serial No. 18,153. Term of patent 3½ years.

To all whom it may concern:

Be it known that I, ANTONIO GOVERNATE, a citizen of the United States, residing in Brooklyn, county of Kings, and State of New York, and doing business at 5510 Avenue N, in said city, have invented a new, original, and ornamental Design for Panel for Bedstead Ends, of which the following is a specification, reference being had to the accompanying drawing, forming part thereof.

The figure is a front view of the panel for bedstead ends.

The panel is a complete article of manufacture apart from the bedstead end.

I claim;

The ornamental design for a panel for bedstead ends as shown.

ANTONIO GOVERNATE. [L.S.]
